UNITED STATES PATENT OFFICE.

HUGH W. KIMES, OF DAYTON, OHIO, ASSIGNOR TO THE STILWELL-BIERCE & SMITH-VAILE COMPANY, OF SAME PLACE.

DESIGN FOR A PUMP-HOUSING.

SPECIFICATION forming part of Design No. 28,548, dated May 3, 1898.

Application filed February 7, 1898. Serial No. 669,455. Term of patent 14 years.

To all whom it may concern:

Be it known that I, HUGH W. KIMES, a citizen of the United States, residing at Dayton, in the county of Montgomery and State of Ohio, have invented and produced a new and original Design for a Housing for Pumps; and I do declare the following to be a full, clear, and exact description of the same, reference being had to the accompanying drawings, forming a part thereof.

Figure 1 is an elevation of either side of a pump-housing constructed in accordance with my design. Fig. 2 is a perspective view of my design for a pump-housing.

As is shown in the drawings, the leading or material features of my design comprise a pump-housing having two end and two intermediate journal-boxes and consisting of two sides A B, which taper outwardly from top to bottom, with four bearings at their upper terminals—to wit, two end bearings C D and two intermediate bearings E F. Each side of said housing consists of four upright standards C' D' and E' F' in vertical lines with the bearings C D and E F and which are united

or tied together by two horizontal integral bars G H and a bottom flange I. On each side of said standards and on each side of the tie-bars G H there are two series of openings J J', through which access is had to the interior of the housing. The sides are joined at their ends by integral walls K, that cross above an oblong opening L and through which there is an opening M.

N designates vertical guides interposed between the standards.

On each of the end walls K there is a vertical strengthening-rib K', that joins the end bearings C D.

Having described my invention, what I claim as new, and desire to secure by Letters Patent, is—

The design for a pump-housing, as herein shown and described.

In testimony whereof I affix my signature in presence of two witnesses.

HUGH W. KIMES.
